UNITED STATES PATENT OFFICE.

HENRY DRESES, OF CINCINNATI, OHIO.

FEEDING MECHANISM IN METAL-WORKING MACHINERY.

1,231,721.

Specification of Letters Patent.

Patented July 3, 1917.

Application filed July 2, 1915. Serial No. 37,760.

To all whom it may concern:

Be it known that I, HENRY DRESES, a citizen of the United States, residing at Cincinnati, in the county of Hamilton and State of Ohio, have invented certain new and useful Improvements in Feeding Mechanism in Metal-Working Machinery, of which the following is a specification.

My invention relates to feeding mechanism for feeding the tool in metal working machinery employing an axially feeding tool, and is applicable, for instance, in drilling machinery and other machinery employing a drilling, tapping, boring or similar tool, and is exemplified as applied in a so-called drilling machine.

It is the object of my invention to provide novel means whereby the distance of axial movement of the tool is controlled, and further, to provide novel controlling means acting on the tool-spindle for setting its limit of axial movement at a definite point irrespective of the number of repetitions of said movement. I have herein shown and described novel means for counterbalancing the tool-spindle which are compact in structure, comparatively short in movement of the moving parts, and so arranged as to be a self-contained structure with the tool-feeding mechanism, but I do not herein claim said means for counterbalancing the tool-spindle, but show, describe and claim the same in an application which is divisional hereof, being Serial No. 60,295, filed November 8, 1915, and issued as Patent No. 1,181,580, dated May 2, 1916.

The invention will be further readily understood from the following description and claims, and from the drawing, in which latter:

Figure 1 is a front elevation of so much of a drilling machine as is necessary to illustrate my invention.

Fig. 2 is an enlarged front elevation of my improved mechanism.

Fig. 3 is a plan view of the same.

Fig. 4 is a cross-sectional detail taken on the line 4-4 of Fig. 2, showing a bottom view of the control mechanism.

Fig. 5 is a vertical section of the same taken on the axial line of the feed shaft, on the line 5-5 of Fig. 2.

Fig. 6 is a detail in front elevation, showing the shifting means for the two-speed speed-changing mechanism.

Fig. 7 is a vertical section of my improved

device taken on the axial line of the tool-spindle, on the line 7-7 of Fig. 2.

Fig. 8 is a horizontal section of my improved device, taken on a line corresponding to the line 8-8 of Fig. 5.

Fig. 9 is a cross-section of the same taken on a line corresponding to the irregular line 9-9 of Fig. 5.

Fig. 10 is a detail in front elevation of the four-speed speed changing means, partly in section on the line 10-10 of Fig. 10^a.

Fig. 10^a is a cross-section of the same on the line 10^a-10^a of Fig. 10.

Fig. 11 is an end elevation of my improved device.

Fig. 12 is a cross-sectional detail taken on a line corresponding to the line 12-12 of Fig. 11.

Fig. 13 is a vertical section showing details of the control mechanism, taken on the line 13-13 of Fig. 12.

Fig. 14 is a cross-sectional detail taken on the line 14-14 of Fig. 11, showing the counterweight mechanism.

Fig. 15 is a vertical section of the same taken on a line corresponding to the line 15-15 of Fig. 14.

In the present exemplification of my invention, 15 represents the radial drill-arm, which is arranged to have suitable movement up and down and about a column designated generally as 16. A suitable tool-housing, shown as a drill-head 17 is provided. It is shown mounted on a slide 18, arranged to slide laterally on guideways 19 on the drill-arm, being adjusted by a hand-wheel 20 which rotates a suitable pinion 21 meshing with a rack 22 extending lengthwise of the drill-arm, and arranged to place the drill-head at suitable points along the drill-arm, as is usual in structures of this character, for positioning the tool, as the drill 23, with relation to the material, represented as a casting 24.

26 represents the drive-shaft which in the present exemplification is arranged to provide the driving force for rotating and also for feeding the drill-spindle 27, at the lower end of which the drill 23 is secured. The shaft 26 is arranged to be driven in suitable or usual manner for having different speeds imparted thereto by power, depending on the character of operations it is desired to perform.

A hub 31 has spline-connection 32 with the drive-shaft and is arranged to be moved

lengthwise along the drive-shaft, as by being journaled in a bearing 33 of a bracket 34 extending from the slide 18 of the drill-head. (See Figs. 7, 8, 9 and 11). This hub has a bevel-gear 35 thereon, which meshes with a bevel-gear 36 on a shaft 37 journaled in a bearing 38 on the slide and having a second bevel-gear 39 secured thereto.

The drill-head is arranged to be adjusted about the axis of rotation of the shaft 37 for placing the drill-spindle in upright position or at an angle with relation to the work. The drill-head is guided in this adjustment by an annular guideway 40 on the slide and is arranged to be clamped in adjusted position, as by clamp-bolts 41, extending through holes 42 in the drill-head, the heads of the bolts being received in an annular T-slot 43 in the slide, nuts 44 clamping the parts together.

The bevel-gear 39 meshes with a bevel-gear 46, the hub of which is journaled in a bearing 47 of the drill-head and has spline-connection 48 with the drill-spindle for rotating the drill-spindle in its bearings 49 of the drill-head.

A second bevel-gear 50 is secured to and rotates with the bevel-gear 46 and meshes with a bevel-gear 51 fast on a shaft 52 journaled in a bearing 53 of the drill-head and at its other end carrying spur-gears 54 of different diameters fast thereon, forming a nest of gears. (See Figs. 3, 5, 8 and 9).

The gears 54 mesh respectively with gears 55 of a coacting nest of gears arranged to be selectively secured to a shaft 57, exemplified as accomplished through a ducking key 58. This key is on a key-bar 59 sliding in a groove 60 in the shaft 57 and pressed toward key-slots 61 in the gears 55, by a spring 62. A separating collar 63 insures engagement of the key with only one gear at a time. The key-bar is connected at its inner end at 64 with a sleeve 65 having longitudinal movement on the shaft 57 and controlled by a lever 66. The lever is pivoted on a shoulder-bolt 67, and has a fork 68 thereon which is received about a pin on an extension 69 of the sleeve, said extension being guided in a slot 70 in the drill-head, for moving the sleeve. (See Figs. 5, 6, 8 and 9).

A shaft 71 is in line with the shaft 57 and is journaled in a bearing 72, the shaft 57 being journaled in a bearing 73. The shaft 71 has a hollow inner end 74 in which the outer end of the shaft 57 is received. A clutch 75 is located between the shafts 57 and 71 for forming drive-connection between said shafts or releasing the drive-connection of shaft 57 from the shaft 71. The said clutch is exemplified as a toothed clutch, the teeth of which are respectively on the end of a shaft 71 and on a clutch-collar 76 which has spline-connection 77 with the shaft 57.

Gears 80 forming a nest of gears of different diameters are fixed on the shaft 71. The shaft 71 is held against endwise movement by locating its bearing between said nest of gears and the annular flange 81 carrying the clutch-teeth formed on said shaft. The shaft 57 is held against endwise movement by locating its bearing between the gears 55 and a collar 82 fast on said shaft. 70

Movement of the clutch-collar 76 is controlled by a lever 86, which is fulcrumed on a shoulder bolt 87 on the drill-head and is provided with a fork 88 received in the annular groove 89 of the clutch-collar, the fork being pivoted by its pin 90 in a bearing 91 of said lever. (See Figs. 8, 9 and 12). The movement of the lever controls the clutched or unclutched relation of the clutch, whereby feeding movement is imparted to the drill-spindle or said feeding movement is stopped. 80

The respective gears of the nest of gears 80 mesh with the gears of a nest of gears 93 of different diameters normally loose on a shaft 94 but arranged to be selectively fixed 90 to said shaft in suitable manner, as by a ducking key 95. (See Figs. 8, 9 and 10). Collars 96 about the shaft 94 between said gears of the nest of gears 93 prevent simultaneous meshing of said key with more than 95 any one of the gears of said nest of gears. The key is arranged to make engagement with said gears by being received in the selective key-slots 97 in the bores of said gears. The ducking key is on a key-bar 98 sliding 100 in a groove 99 in the shaft 94 and pressed toward the key-slots by a spring 100. The key-bar has connection 101 with a slide 102 having slide bearing on the shaft 94. 100

The shaft 94 is journaled in bearings 103 on the drill-head. The slide 102 is provided with a rack 105 with which a pinion 106 meshes, the pinion being on a shaft 107 rotating in a bearing 108 of the drill-head and having a handle 109 fast thereon for 110 rotating the shaft, (see also Figs. 2, 7, 10 and 10^a), the handle being provided with the pointer 110 arranged to register with the respective markings of a gage 111 on the drill-head for indicating the position of 11 the ducking key.

The speed of feed of the spindle is determined by the drive-connection between the shafts 71 and 94 through the respective gears of the nests of gears 80 and 93, for 12 imparting four different speeds of feed to the drill-spindle. In the present instance these speeds are multiplied by two by engagement of the ducking key 58 with the respective gears 55.

A feed-shaft 114 is provided. A worm 115 is fast on the shaft 94 and meshes with a worm-wheel 116 which is fast on a bushing 117 journaled in a bearing 118 of the drill-head and prevented from endwise movement 1

by the annular flange 119 of said bushing at one end of said bearing and the worm-wheel fast on said bushing at the other end of said bearing.

- 5 The feed-shaft is rotatable in said bushing when it is desired to impart a speedy rotation by hand to the feed-shaft, for rapidly raising or lowering the drill-spindle, and said bushing is arranged to be fixed to said feed-shaft during the feeding movement of the drill spindle, this selective attachment or detachment of the worm-wheel with the feed-shaft being accomplished by means of a clutch 120 exemplified as a toothed clutch, 70
10 the teeth of which are respectively located on the bushing 117 and a hub 121. (See Figs. 2, 5 and 11).

The hub 121 is slidable lengthwise on a bushing 122. The bushing 122 is fixed to 20 the feed-shaft, as by key and pin connection as shown. The hub 121 has spline-connection 124 with the bushing for disengagement of the clutch 120 when it is desired to rotate the feed-shaft by hand for quick axial movement 25 of the drill-spindle, or for engagement of said clutch when it is desired to rotate the feed-shaft by power or by means of a hand-wheel 125 for feeding the drill-spindle. The hub 121 is provided with a cap 126, a rod 30 127 extending inwardly from said cap into the hollow 128 in the end of the feed-shaft. The inner end of the rod is provided with a collar 129 fixed thereon between which and a collar 130, fixed in the outer end of the 35 hollow of said shaft, a helical spring 131 is arranged for normally pressing the cap and consequently the hub 121 upwardly for normal engagement of the clutch 120.

The hub 121 is moved axially by means of 40 arms 134 pivoted on pins 135 to the hub and having knobs 136 at their inner ends received in an annular groove 137 in the bushing 122. If it is desired to impart quick rotation to the feed-shaft without rotating the worm-wheel, downward pressure is exerted upon the outer ends of any one of the arms 134, whereby the hub is pushed away from the bushing 117 for disengaging the clutch 120, whereupon the hub may be turned by means of the arms for quick axial movement 45 of the drill-spindle, a pin 138 guided in a hole 139 in the hub being spring-pressed by a spring 140 into a notch 141 in the bushing 122 for holding said hub in down position and the clutch in unclutched relation 50 when one of the arms 134 has been manipulated for the purpose, a slight upward blow or push on any one of said arms moving said pin out of its notch and causing reengagement 55 of said clutch by the action of said spring 131.

The connection between the feed-shaft and the spindle in the present exemplification is accomplished by providing the feed-shaft 60 with a bevel-pinion 143 which meshes with a

bevel-gear 144 on a shaft 145. This shaft is provided with a pinion 149 which meshes with a rack 150 on a rack-sleeve 151 slidable lengthwise in a bearing 152 in the drill-head, the drill-spindle having a reduced end 70 153 extending through said sleeve, the said sleeve and drill-spindle having combined axial movements. (See Figs. 7, 11 and 14.) There is preferably a ball bearing 154 between the lower end of the sleeve and the 75 annular shoulder 155 on the drill-spindle, the upper end of the drill-spindle being provided with a bearing 156 for the upper end of the sleeve.

In order to control the limit of feeding 80 movement of the drill-spindle, for instance for arranging the drill-spindle for separately drilling a plurality of holes of equal depths in material, and for other purposes, I provide novel controlling mechanism for the 85 depth of feed of the drill-spindle.

In the present exemplification of this device, (see Figs. 2, 4, 5, 11, 12 and 13), 161 represents a plate, shown provided with a hub, which rotates about the feed-shaft 114 90 and is positioned by a collar 162 fast on the feed-shaft. This plate is in the form of a housing and has a recess 163 in which there is a ring 164 provided with internal teeth 165.

A companion plate 166 is provided with a hub about the feed-shaft and is held toward the plate 161 by a collar 168 fast on the feed-shaft. The plate 166 is provided with a stud 169 on which a pinion 170, which meshes 95 with the internal teeth 165, rotates, this pinion also meshing with a pinion 167, the teeth of which are cut in the feed-shaft. The plate 166 is prevented from rotating by being provided with a pin 171 which is received in a slot 172 of a retaining part 173 secured to the drill-head. The plate 161 is arranged to be selectively secured to the ring 164 and it is also provided with a striker-part 174, shown as a striker-pin. 100

The striker-pin 174 is arranged to coact with a striker-part 175 adjustable on the lever 86, which controls the clutch 75. The striker-part 175 is adjustable in a slot 176 of a lug 177 on the lever and has a slot 178 through which a clamp-bolt 179 passes into the lug for clamping the striker-part in adjusted position to the lever. 110

When the striker-part 174 strikes the striker-part 175 the said clutch is thrown 120 into disengaged relation, and the time of this striking is controlled by the position of the plate 161 with relation to the ring 164, this positioning being indicated by a gage 180, the markings of which are shown 125 on the inverted frusto-conical face 181 of the plate 161 and the coacting finger 182. The striker-part 175 on said lever is provided with inclined faces 183 coacting with the striker-part 174 for ease of operation. 130

The lever 86 is provided with a handle 184 for manual control of the clutch 75.

It will be noted that the feed-shaft is inclined, the controlling device being correspondingly inclined, the markings of the gage being on the inverted frusto-conical face of the control device for placing said markings in convenient position for being read.

10 For positioning the relation between the plate 161 and the ring 164, I provide one or more pull pins 186. The inner end of the pins 186 is provided with a tooth 187 arranged to engage in the toothed spaces of the external teeth 188 on the ring 164, its outer end having a knob 189. A pin 190 located in a hole 191, closed by a plug 192, screw-threaded in the outer end of said hole, and pressed inwardly by a spring 193, is arranged to engage either one of the recesses 194 for holding said tooth-pin in engaging or disengaged position with relation to said ring.

When it is desired to control the depth to which the drill shall enter a piece of work, the drill is fed axially either by hand or power, so that its point will be in the plane of the face of the work it is desired that the drill shall enter, as shown in Fig. 1, whereupon the feed of the drill is stopped. The teeth 187 are then pulled outwardly to disengage the ring 164, which releases the plate 161, which is then free to turn about the feed-shaft. The plate is then turned manually until the desired marking on its gage 180, representing the desired depth of the hole about to be drilled, is opposite the pointer 182.

For instance, if it is desired to drill a hole of two inches depth, the plate 161 is turned until the marking "2" representing two inches on the gage 180 is opposite the pointer 182, whereupon the tooth-pins 186 are pushed inwardly for causing the teeth 187 at their inner ends to engage the spaces between the teeth at said point of adjustment located in the ring 164.

When now the feed-shaft is caused to turn, the pinion 170 is caused to rotate for imparting motion to the ring 164, which is thereby caused to turn for rotating the plate 161.

It may be here stated that the striker-part 174 is located at the zero position of the gage 180, and that in the adjustment of the plate 161 the striker-part 174 thereon has been distanced from the striker-part 175 an angular distance corresponding to the arc of movement of the striker-part 174 during the desired axial drilling movement of the drill-spindle. The speed of this angular movement is substantially greater than the speed of said axial movement, owing to the structure and arrangement of the parts 65 so that minute subdivision of the gage and

accuracy in depths of holes cut is obtained. The movement of the gage is preferably reverse to the direction of rotation of the feed-shaft.

The striker-part 174 travels this angular 70 distance and at the end of this travel it strikes the striker-part 175 for disengaging the clutch 75. Upon disengagement of this clutch the axial feed of the spindle ceases. The spindle is then raised for drawing the 75 tool out of the work, and the work shifted, or another piece of work substituted, and the operation repeated without readjustment of the parts as many times as desired.

For causing quick disengagement of the 80 clutch 75, the lever 86 is provided with a pin 196 whose end is provided with inclined faces 197 which coact with the inclined faces 199, on a pin 201 on the drill-head. One of the pins, instanced as the pin 201, is 85 spring-pressed by a spring 202 toward the other pin, instanced as the pin 196, the advancing movement between the inclined faces 197, 199, causing retreat of the pin 201. As soon as the apex of pin 196 passes 90 the apex of the pin 201, the inclined faces being spring-pressed toward each other, will cause rapid movement of the lever for disengaging the clutch with a quick movement. Corresponding quick reverse movement and 95 therefore quick engagement between the clutch teeth is also assured by this device.

I have in my improved device provided novel means for counterbalancing the drill-spindle by means in which a counterweight 100 is provided which has a comparatively short range of movement and is self-contained with the drill-head. (See Figs. 7, 11, 14 and 15). Thus 204 is a counterweight which has movement lengthwise of the upward extension 205 of the drill-head. The counterweight is provided with a guideway 206 co-acting with a guide 207 on said upward extension. A rod 208 is secured in a lug 209 of said upward extension and slides in a 110 bearing 210 on said counterweight. The counterweight is also provided with a rack 211 with which a pinion 212 on the shaft 145 meshes. This construction forms operating and guiding means for the counterweight.

The pinion 149 which meshes with the rack for axial feed of the tool-spindle and the pinion 212 which meshes with the rack 211 on the counterweight are both fast on 120 the same shaft, the rack of the drill-spindle and the rack of the counterweight engaging said pinions respectively at opposite sides of said shaft, so that the weight of the counterweight acting downwardly upon one side of 125 the pinion 212 forces the opposite side of the pinion 149 upwardly for balancing the weight of the drill-spindle.

It will be further noticed that the pinion 149 is larger than the pinion 212. A given 130

axial movement of the drill-spindle will therefore result in a less distance of movement of the counterweight, so that the distance through which the counterweight 5 moves is comparatively short, thereby necessitating only a correspondingly short range of space for permitting this movement and resulting in economy of space in the structure and providing a self-contained counter-10 balancing structure for the drill-spindle.

The shaft 145 has the pinions 149, 212, formed thereon. The bevel-gear 144 is fast on the shaft 145. A bushing 213 is fast in a bearing 214 of the drill-head. A bushing 15 215 is received about the shaft 145 between the gear 149 and the rack 150 and is fast in a bearing 216 of the drill-head. The shaft 145 rotates in the bushings 213, 215, and is held in place thereby.

20 Having thus fully described my invention, what I claim as new and desire to secure by Letters Patent, is:

1. In feeding mechanism of the character described, the combination of a tool-spindle, 25 a feed train of gearing for feeding said tool-spindle axially comprising a drive-shaft, a rotatable shaft and a clutch, a tripping mechanism for said clutch comprising a member adjustable for angular distance of 30 movement about the axis of rotation of said rotatable shaft for adjustably fixing the moment of tripping of said tripping mechanism, and a train of gearing between said rotatable shaft and said member for rotating 35 said member.

2. In a feeding mechanism of the character described, the combination of a tool-spindle, a feed train of gearing for feeding said tool-spindle longitudinally comprising 40 a drive-shaft, a rotatable shaft and a clutch, a rotatable member having an annular gage thereon, a trip on said rotatable member in radial line with the zero position of said gage, a coacting trip therefor having operative connection with said clutch for tripping the same, said rotatable member adjustable about the axis of rotation of said rotatable shaft for positioning the graduations of said gage with relation to said coacting trip, and 45 50 a train of gearing between said rotatable shaft and said rotatable member for rotating said rotatable member.

3. In a feeding mechanism of the character described, the combination of a tool-spindle, 55 a feed train of gearing for axially feeding said tool-spindle comprising a drive-shaft, a clutch and a rotatable shaft, clutch-operating means, a rotatable element about the axis of rotation of said rotatable shaft 60 provided with a substantially peripheral gage and with a tripper-part for said clutch-operating means, means for adjusting said rotatable element about said axis according to the markings of said gage for adjusting 65 the radial position of said tripper-part, and

a train of gearing between said shaft and rotatable element for rotating the latter in predetermined relation with the axial movement of said tool-spindle.

4. In a drilling machine, the combination 70 of a drill-head, an axially movable drill-spindle therein, a drive-shaft, a feed train of gearing for longitudinally feeding said drill-spindle mounted on said drill-head and comprising a clutch and a feed-shaft, said 75 drive-shaft having operative connection with said feed train of gearing for driving the same, means for operating said clutch, a control means for said last-named means comprising a rotatable element about said feed-shaft and a control-part for said clutch-operating means, a train of gearing between said feed-shaft and said rotatable element, and means for adjusting the relation between 80 said last-named train of gearing and said rotatable element for controlling the moment of coöperation of said control-part with said clutch-operating means.

5. In a drilling machine, the combination 85 of a drill-head, an axially movable drill-spindle therein, a drive-shaft, a feed train 90 of gearing for longitudinally feeding said drill-spindle mounted on said drill-head comprising a clutch and a feed-shaft, said drive-shaft having operative connection 95 with said feed train of gearing for driving the same, means for operating said clutch, a control means for said last-named means comprising a rotatable element about said feed-shaft and a control part for said clutch-operating means, a train of gearing between 100 said feed-shaft and said rotatable element, means for adjusting the relation between said last-named train of gearing and said rotatable element for controlling the moment of coöperation of said control-part 105 with said clutch operating means, a slide, and means for selectively adjusting said drill-head on said slide whereby the direction in which said tool-spindle extends is 110 adjusted with relation to the vertical and the others of said aforementioned parts are maintained in their relations with said tool-spindle, for the purpose described.

6. In feeding mechanism of the character 115 described, the combination of a tool-spindle, a feed train of gearing for axially feeding said tool-spindle comprising a drive-shaft, a rotatable shaft and a pair of clutches, a rotatable element having operative connection 120 with one of said clutches for operating the same, said rotatable element adjustable about the axis of rotation of said rotatable shaft for controlling its moment of operation of said last-named clutch, and means 125 for manually operating the other of said clutches for interrupting said feed train of gearing and placing said spindle feed under manual control of the operator.

7. In a feeding mechanism of the charac- 130

ter described, the combination of a tool-spindle, a feed train of gearing for axially feeding said tool-spindle, said feed train of gearing comprising a drive-shaft and a feed-shaft, a gear on the latter, a rotatable element about the axis of rotation of said feed-shaft, an internal gear, means for adjustably connecting said internal gear and said rotatable element, said gear on said feed-shaft having gear connection with said internal gear, said feed train of gearing comprising gearing between said drive-shaft and said feed-shaft including a clutch and said rotatable element having a clutch operating part thereon adjusted for determining its moment of operation by said adjustment of said rotatable element.

8. In a feeding mechanism of the character described, the combination of a tool-spindle, a feed train of gearing for axially feeding said tool-spindle, said feed train of gearing comprising a drive-shaft and a feed-shaft, a gear thereon on said feed-shaft, a rotatable element about the axis of rotation of said feed-shaft, an internal gear, means for adjustably connecting said internal gear and said rotatable element, said gear on said feed-shaft having gear connection with said internal gear, said feed train of gearing comprising gearing between said drive-shaft and said feed-shaft including a clutch and said rotatable element having a clutch operating part thereon adjusted for determining its moment of operation by said adjustment of said rotatable element, a second clutch in said feed train of gearing, and manually operating means therefor whereby said last-named clutch is interrupted and said feed-shaft placed under manual control of the operator.

9. In a feeding mechanism of the character described, the combination of a tool-spindle, a feed train of gearing for axially feeding said tool-spindle comprising a drive-shaft, a feed-shaft, and a clutch between said shafts, a clutch operating part, a rotatable member about said feed-shaft having a clutch controlling part thereon coacting with said clutch operating part, an internal gear for said rotatable member, means for adjustably connecting said rotatable member and said internal gear for determining the moment of operation of said clutch operating part, and a gear on said feed-shaft, said last-named gear being in train with said internal gear.

10. In a feeding mechanism of the character described, the combination of a tool-spindle, and means for axially feeding said tool-spindle comprising a drive-shaft, a slanting feed-shaft, a rotatable member adjustable thereabout, and a clutch between said shafts, said rotatable member having a substantially inverted frusto-conical peripheral face having indicating means

thereon for indicating the extent of said adjustment, a clutch operating member, said rotatable member having a tripping part thereon coacting with said clutch operating member and adjusted by the adjustment of said rotatable member about said feed-shaft.

11. In feeding mechanism of the character described, the combination of a tool-spindle, a feeding train of gearing for axially feeding said tool-spindle comprising a drive-shaft, a slanting shaft and a clutch between said shafts, a clutch operating means, a rotatable element about said slanting shaft having a tripping part thereon coacting with said clutch operating means, means for adjusting said rotatable element about said slanting shaft, and means for rotating said rotatable element from said slanting shaft at a reduced speed with relation thereto.

12. In feeding mechanism of the character described, the combination of a tool-spindle, a power train of gearing for axially feeding said tool-spindle comprising a drive-shaft, a slanting shaft and a clutch, a clutch operating means, a rotatable element about said slanting shaft having a tripping part thereon coacting with said clutch-operating means, means for adjusting said rotatable element about said slanting shaft, means for rotating said rotatable element from said slanting shaft at a reduced speed with relation thereto, a manually rotatable means for said slanting shaft, and a clutch between said power train of gearing and said manually rotatable element for interrupting the operative connection between said power train of gearing and said slanting shaft and placing said slanting shaft under manual control of the operator.

13. In a feeding mechanism of the character described, the combination of a tool-spindle, a power train of gearing for axially feeding said tool-spindle comprising a drive-shaft, a feed-shaft, a clutch between said drive-shaft and said feed-shaft, a clutch operating part, a rotatable member about said feed-shaft having a control-part thereon for said clutch-operating part, and means for rotating said rotatable member from said feed-shaft.

14. In a feeding mechanism of the character described, the combination of a tool-spindle, a power train of gearing for axially feeding said tool-spindle comprising a drive-shaft, a feed-shaft, a clutch between said drive-shaft and said feed-shaft, a clutch operating part, a rotatable member about said feed-shaft having a control-part thereon for said clutch operating part, means for rotating said rotatable member from said feed-shaft, and a manually controlled clutch between said last-named clutch and said feed-shaft.

15. In a feeding mechanism of the character described, the combination of an axi-

- ally feedable tool-spindle, a feed train of gearing for axially feeding said tool-spindle comprising a drive-shaft, a feed-shaft and a clutch, a rotatable member having a part thereon arranged for operating said clutch, an internal gear, gearing between said feed-shaft and internal gear for rotating said internal gear, and means for adjusting the operative connection between said internal gear and said rotatable member for controlling the moment of actuation of said clutch. 5
16. In feeding mechanism of the character described, the combination of an axially feedable tool-spindle, a feed train of gearing for axially feeding said tool-spindle comprising a drive-shaft, a feed-shaft and a clutch, means for operating said clutch comprising a rotatable member journaled about the axis of rotation of said feed-shaft, an internal gear, a gear on said feed-shaft, gearing between said last-named gear and said internal gear for rotating said internal gear from said feed-shaft, means for adjustably securing together said rotatable member and said internal gear, and a tripper part on said rotatable member coöperating with said clutch. 10
17. In feeding mechanism of the character described, the combination of an axially feedable tool-spindle, a feed train of gearing for axially feeding said tool-spindle comprising a drive-shaft, a feed-shaft and a clutch, a pair of plates received about said feed-shaft, an external gear and an internal gear between said plates, said external gear journaled to one of said plates, means for adjustably securing the other of said plates to said internal gear, and tripping means 15 on said last-named plate for tripping said clutch, said tripping means movable with said last-named plate for adjusting the tripping moment of said clutch. 20
18. In feeding mechanism of the character described, the combination of an axially feedable tool-spindle, a feed train of gearing for axially feeding said tool-spindle comprising a drive-shaft, a slanting shaft and a clutch, an upper plate and a lower plate received about said slanting shaft, an external gear and an internal gear between said plates, said external gear journaled to one of said plates, means for adjustably securing the other of said plates to said internal gear, tripping means and 25 an inverted frusto-conical gage on said last-named plate, said tripping means movable with said last-named plate for adjusting the tripping moment of said clutch, and a coacting tripper-part having operative connection with said clutch. 30
19. In feeding mechanism of the character described, the combination of an axially feedable tool-spindle, a drive-shaft therefor, a feed-shaft in train with said tool-spindle, a shaft in train with said drive-shaft, speed changing mechanism between said last-named shaft and said feed-shaft whereby a plurality of different speeds are imparted to said feed-shaft, a clutch for operatively connecting said speed changing mechanism with said shaft in train with said drive-shaft, a rotatable member about said feed-shaft, tripping means on said rotatable member for said clutch, driving means between said feed-shaft and said rotatable member, and means for adjusting the operative relation between said driving means and said rotatable member for adjusting the tripping moment of said trip- 35 ping means. 40
20. In feeding mechanism of the character described, the combination of an axially feedable tool-spindle, a drive-shaft therefor, a feed-shaft in train with said tool-spindle, a shaft in train with said drive-shaft, said train comprising a speed changing mechanism, speed changing mechanism between said last-named shaft and said feed-shaft whereby a plurality of different 45 speeds are imparted to said feed-shaft, a clutch for operatively connecting said speed changing mechanism with said shaft in train with said drive-shaft, a rotatable member about said feed-shaft, tripping means on said rotatable member for said clutch, driving means between said feed-shaft and said rotatable member, and means for adjusting the operative relation between said driving means and said rotatable member for adjusting the tripping moment of said trip- 50 ping means. 55
- In testimony whereof, I have hereunto signed my name in the presence of two subscribing witnesses.

HENRY DRESES.
